UNITED STATES PATENT OFFICE.

WILLIAM Y. STROH AND GEORGE W. KLAGES, OF PITTSBURGH, PENNSYLVANIA.

HAMMERING APPARATUS.

Application filed January 24, 1920. Serial No. 353,665.

To all whom it may concern:

Be it known that we, WILLIAM Y. STROH and GEORGE W. KLAGES, both citizens of the United States, residing at Pittsburgh, Allegheny County, Pennsylvania, have invented a new and useful Improvement in Hammering Apparatus, of which the following is a full, clear, and exact description, reference being had to the accompanying drawings, forming part of this specification, in which:

Figure 1 is a side elevation of a preferred form of apparatus embodying our invention.

Figure 2 is a vertical section of the same.

Figure 3 is a face view of the hammers on a larger scale.

Figure 4 is a section on the line IV—IV of Figure 1, and

Figure 5 is a detail sectional view showing the spring seats.

Our invention has relation to hammering apparatus; and is designed to provide an apparatus of this character which is especially applicable for use in finishing castings by the hammering method described and claimed in the co-pending application of William Y. Stroh, one of the applicants herein, and James Thompson, Serial No. 348,336, filed Dec. 30, 1919.

In accordance with the method described in that application, castings are made which are of substantially the contour of the finished article desired; and these castings are finished by subjecting them, or certain surfaces thereof, to a hammering action by means of which such surfaces are brought to the desired contour and degree of smoothness and may also be polished. The apparatus formed in the subject matter of the present application provides means whereby such method may be carried out in an entirely satisfactory and efficient manner.

The nature of our invention will be best understood by reference to the accompanying drawings in which we have shown a preferred embodiment of our invention, and which will now be described, it being premised, however, that various changes can be made in the details of construction, arrangement and combination of the parts without

departing from the spirit and scope of our invention as defined in the appended claims.

In these drawings the numeral 2 designates a supporting frame or housing having a base portion which is preferably provided with guides 3 whereby it may be movably mounted upon a suitable support and also having an upright portion 2^a in which certain of the movable parts hereinafter described are mounted.

4 designates a shaft which is mounted in the lower part of said upright portion, in suitable bearings 5 and which is driven in any suitable manner, not shown. Said shaft 4, between the side plates of the upright portion of the frame or housing, has a plurality of eccentrics 6, four in number in the present case. Each of these eccentrics is surrounded by a strap 7 having a depending toe 8 and an upwardly extending lever arm 9.

Each of these lever arms extends through a slot in an oscillating member 10 which is movably seated in a vertically movable slide box 11 mounted in ways or guides 12 of the housing portion 2^a. This slide box may be moved by any suitable means, as by the links 13 connected to opposite ends thereof and also connected to the lever arms 14 of a rocker shaft 15, said shaft provided at one

end portion with an actuating lever 16 which may be held in different adjusted positions by a bolt 17 arranged to work in a slot 18 of the holding member 19. It will be readily seen that by moving the lever 16 to different positions the slide box can be raised or lowered; and as the member 10 carried in

said slide box forms the fulcrums for the eccentric levers, the adjustment of said slide box will vary the effective stroke of the toes 8. These toes 8 are arranged to retract the hammer elements after each blow of the latter. These elements, designated at 20, are removably secured on the outer ends of the plungers 21 which are mounted for reciprocation in suitable guides 22 in the frame or housing. Said elements may take various forms according to the particular nature of the work to be performed. In the form shown they have a relatively limited contact portion 23 extending trans-

100

versely thereof; and, preferably, these contact portions, as shown in Figure 3, are staggered or out of line with respect to each other. The said elements have offset lateral edges so as to interfit with each other in the manner indicated in this figure, and thereby strike partially overlapping blows.

The striking impulse is imparted to each plunger by means of a spring 24 seated at 10 one end against a shoulder 25 on the plunger and at the opposite end in a pocket 26 of a seating block 27. This block is slidably mounted in suitable guides 28 in the frame or housing; and each pocket is preferably provided with a follower 29 which is independently adjustable by means of a screw 30. The slide block 27 can also be adjusted as a unit to correspondingly vary the compression of all the springs by any 20 suitable means such as that shown. Such means consist of a hand lever 31 secured to a transversely extending rock shaft 32 and having lever arms 33 at opposite ends which bear against the studs 34 on said block. When the lever 31 is actuated, the block can be moved forwardly against the action of the springs, or can be allowed to move backwardly under the action of the springs. The desired adjustment is secured 30 by providing the lever members 33 with slots 34^a having the locking device 35.

Each of the plungers 21 is provided with the shoulder 36 for engagement with one of the toes 8 whereby, under the action of the 35 eccentric, said plunger is retracted against the action of its spring until the predetermined compression of the spring is reached, when the plunger is disengaged by said toe and is impelled in a striking direction by the action of the spring. The several eccentrics are at different angles, as indicated in Figure 4, so that the series of hammer elements strike successive blows.

It is frequently desirable to provide means 45 whereby one or more of the hammer elements may be drawn out of action. For this purpose, we provide a rock shaft 37 having a series of fingers 38, each of which is designed to engage a shoulder 39 formed 50 on the underside of the corresponding plunger. The shaft 37 is provided with an actuating lever 39^a. When this lever is moved downwardly from its normal position, shown in Figure 1, the fingers 38 will engage the plungers to retract them. Any desired plunger or plungers may then be locked in this retracted, inoperative, position by inserting a pin through one of the 55 holes 40, provided therefor in the frame 60 or housing and into engagement with the registering hole 41 in the plunger. Or, by inserting the spring pin 41^a in the hole 41^b, all the plungers may be held retracted.

The operation of the machine will be read-

ily understood by the foregoing description 65 thereof.

The shaft 4 being continuously rotated, the series of hammer elements will strike a rapid and continuous succession of blows. For the purpose described, it is desirable 70 that means be provided whereby the maximum stroke of each hammer element in the striking direction is limited. For this purpose each of the plungers is provided with a shoulder 42 which, at the limit of the 75 striking blow, contacts with a stop block 43 secured in the frame or housing. In this manner each striking blow is stopped at a predetermined maximum point so that the effect upon the casting being finished is 80 to reduce its surface irregularities to the desired plane and prevent hammer indentations beyond such plane. The casting to be finished is supported in any suitable manner with respect to the hammer elements. It may, for instance, be supported on a lathe and revolved to the action of these 85 elements; or it may be placed upon any other suitable support, the character of which will depend upon the form of the casting and the particular surface or surfaces thereof to be finished.

While we have shown the machine provided with four hammer elements, we desire it understood that we are not limited to this particular number, but that a greater or lesser number may be employed as may be desired. In some respects superior work 90 may be done with a single hammer element, although this requires more time.

It will be noted that we provide means whereby the length of stroke of the hammer elements is controlled; means whereby the compression of each spring may be separately adjusted or the entire series of 105 springs simultaneously adjusted; and that means of simple character are provided whereby any one or more of the hammers may be readily thrown out of action. The entire machine is simple in its construction and mode of operation. The hammer elements are preferably removably secured to their plungers so that they can be readily removed and renewed when battered or worn; or may be replaced by other elements 110 having striking faces of different character, according to the particular nature of the work to be done at any time.

To facilitate handling of the apparatus it may be provided with a lifting or suspension ring 44.

We claim:

1. Hammering apparatus comprising a plurality of reciprocating plungers, a hammer element carried by each of said plungers, a spring for each plunger arranged to impart a striking blow thereto, and an eccentric shaft having a plurality of eccen-

- trics at different angles, together with eccentric straps provided each with a toe adapted to engage and retract one of the plungers, substantially as described. 65
- 5 2. Hammering apparatus comprising a plurality of reciprocating plungers, a hammer element carried by each of said plungers, a spring for each plunger arranged to impart a striking blow thereto, an eccentric 70 shaft having a plurality of eccentrics at different angles, and eccentric straps provided each with a toe adapted to engage and retract one of the plungers, together with means for varying the effective throw of the 75 eccentrics, substantially as described.
- 10 3. Hammering apparatus comprising a plurality of reciprocating plungers, a hammer element carried by each of said plungers, a spring for each plunger arranged to 80 impart a striking blow thereto, an eccentric shaft having a plurality of eccentrics at different angles, and eccentric straps provided each with a toe adapted to engage and retract one of the plungers, together with 85 means for simultaneously adjusting the several springs, substantially as described.
- 15 4. Hammering apparatus comprising a plurality of reciprocating plungers, a hammer element carried by each of said plungers, a spring for each plunger arranged to 90 impart a striking blow thereto, an eccentric shaft having a plurality of eccentrics at different angles, and eccentric straps provided each with a toe adapted to engage and retract one of the plungers, together with 95 means for simultaneously adjusting the several springs and also for separately adjusting each spring individually, substantially as described.
- 20 5. Hammering apparatus comprising a plurality of reciprocating plungers, a hammer element carried by each of said plungers, a spring for each plunger arranged to 100 impart a striking blow thereto, an eccentric shaft having a plurality of eccentrics at different angles, and eccentric straps provided each with a toe adapted to engage and retract one of the plungers, together with 105 means for also adjusting each of said springs individually, substantially as described. 110
- 25 6. Hammering apparatus comprising a plurality of reciprocating plungers, a hammer element carried thereby, a spring arranged to impart a striking blow to the plunger, a shaft having an eccentric thereon, an eccentric strap provided with means for engaging and retracting the plunger, said strap also having a lever arm extending therefrom, a fulcrum for said arm, and means for changing the position of said fulcrum, together with means for varying the action of said spring, substantially as described. 115
- 30 7. Hammering apparatus comprising a plunger mounted for reciprocation, a hammer element carried thereby, a spring arranged to impart a striking blow to the plunger, a shaft having an eccentric thereon, an eccentric strap provided with means for engaging and retracting the plunger, said strap also having a lever arm extending therefrom, a fulcrum for said arm, and means for changing the position of said fulcrum, together with means for holding the plunger inoperative in retracted position, substantially as described. 120
- 35 8. Hammering apparatus comprising a plunger mounted for reciprocation, a hammer element carried thereby, a spring arranged to impart a striking blow to the plunger, a shaft having an eccentric thereon, an eccentric strap provided with means for engaging and retracting the plunger, said strap also having a lever arm extending therefrom, a fulcrum for said arm, and means for changing the position of said fulcrum, together with means for holding the plunger inoperative in retracted position, substantially as described. 125
- 40 9. Hammering apparatus comprising a plurality of plungers mounted side by side and provided each with a separate spring for imparting striking blows thereto, eccentric mechanism for retracting said plungers to compress said springs, a sliding seating block provided with seats for a series of springs, and means for adjusting said block to simultaneously vary the action of said springs, substantially as described. 90
- 45 10. Hammering apparatus comprising a plurality of plungers mounted side by side and provided each with a separate spring for imparting striking blows thereto, eccentric mechanism for retracting said plungers to compress said springs, a sliding seating block with a series of springs, and means for adjusting said block to simultaneously vary the action of said springs, together with means for also adjusting each of said springs individually, substantially as described. 100
- 50 11. Hammering apparatus comprising a series of plungers mounted for reciprocation, springs for imparting striking blows to said plungers, an eccentric shaft having a plurality of eccentrics, a strap on each of said eccentrics having a toe portion for engagement with one of the plungers, each of said eccentrics also having a lever arm, a slide block provided with a series of oscillating members through which the lever arms extend and in which they are fulcrumed, and means for adjusting said slide block to different positions, substantially as described. 115
- 55 12. Hammering apparatus comprising a plurality of plungers carrying hammer elements, means for actuating said plungers to cause the hammer elements to make suc-
- 60

cessive striking blows, and means for positively limiting the penetrating action of each hammer element, substantially as described.

5. 13. Hammering apparatus comprising a plurality of plungers, a hammer element carried by each of said plungers, springs for imparting striking blows to the plungers,

means for compressing said springs, and means for limiting the extent of penetrating action of each hammer, substantially as described.

In testimony whereof we have hereunto set our hands.

GEORGE W. KLAGES.
WILLIAM Y. STROH.
